(57) **CLAIM**

The ornamental design for a bottle lid, as shown and described.

DESCRIPTION

FIG. 1 is a top front isometric view of our new design for a bottle lid.

FIG. 2 is a front side elevation view of FIG. 1.

FIG. 3 is a back side elevation view of FIG. 1.

FIG. 4 is a left side elevation view of FIG. 1.

FIG. 5 is a right side elevation view of FIG. 1.

FIG. 6 is a top side plan view of FIG. 1.

FIG. 7 is a bottom side plan view of FIG. 2.

FIG. 8 is an exploded view of the bottle lid.

FIG. 9 is a top front isometric view of the bottle lid of FIG. 1 with the top in the closed position it being understood that all other surfaces are the same as the other views; and, FIG. 10 is a cross sectional view taken along line 10-10 of FIG. 9.

The features shown in broken lines in the drawing show portions of the bottle lid that form no part of the claimed design.
